[57] ABSTRACT

In or for a sewing machine there is a device for assisting the sewing of hooks to tapes or other articles. The hooks are of the kind comprising a length of wire bent to form an open-work base and a bill extending upwards from one side of the base and over part of the base. The device comprises means for supplying hooks sequentially to a hook supply station, and means for engaging the bill of a hook disposed at that station, moving it from the station to a sewing station where the sewing machine can at least start to sew the base to the article, releasing the hook and returning to the hook supply station for a further hook.

FIG. 11.

SEWING MACHINE ATTACHMENTS

This invention relates to sewing machine attachments and aims to provide a sewing machine attachment adapted to assist in the sewing of hooks to tapes or other articles, the hooks being of the kind comprising a base and a bill extending upwards from one side of the base and over part of the base, the base being either of open shape or of a material which can be pierced, so that the hook can be secured to a tape or other article by stitches passing over or through parts of the base.

It must be stated here that throughout this specification, for ease of description and comprehension, all the components are described as if they were in their normal positions; and it is to be understood that this is not intended to restrict the scope of the invention.

In the manufacture of hook tape or other articles to which a row of hooks is secured it is usual to arrange for the base of each hook to be stitched between two of the component layers of the tape or other article, while the bill projects from between the layers, extends upwards past an adjacent edge of the upper layer and over that part of the upper layer adjacent to said edge. The stitching is usually carried out by a sewing machine, and the arrangement may be such that the hooks are secured by means of a straight line of stitches either of uniform length or of different lengths, or by means of more complex patterns of stitches in which some stitches extend laterally, that is in a direction transverse to the direction of material feed. Such lateral stitches can readily be made by a swing-needle sewing machine.

Whatever arrangement is used, however, it is essential that the hooks should be correctly and accurately positioned before they are stitched in place. If a hook is incorrectly positioned there is a likelihood that some part of it will be struck by the needle forming the stitches, and this may cause damage to the hook or the needle, particularly when the hook is made from metal.

An aim of the present invention is to provide means enabling this danger to be avoided or the likelihood of its happening reduced.

In accordance with the present invention there is provided in or for a sewing machine a device for assisting the sewing of hooks to articles, the hooks being of the kind comprising a base and a bill extending upwards from one side of the base and over part of the base, the base having an attachment portion through which a sewing machine needle can pass, the device comprising hook supply means operative to supply hooks sequentially to a hook supply station, hook engaging means operative to engage the bill of a hook disposed at the hook supply station, to move the hook from that station to a sewing station where the attachment portion is aligned with the sewing machine needle, to release the hook and to return to the hook supply station for a further hook.

The device may comprise an attachment for an existing sewing machine, or it may form a part of purpose-built sewing machine.

A significant feature of the invention that each hook is individually taken from the hook supply station to the sewing station by hook engaging means which engages the bill rather than the base of the hook. This enables the hook engaging means to manipulate the base of the hook between two layers of material where it can be

stitched in place as described above. Further, the hook engaging means can readily be arranged to hold each hook at the sewing station while the sewing machine forms at least one stitch for securing the base of the hook to the tape or other article.

In a preferred arrangement the hook engaging means is operative to move the hook laterally with respect to the direction of material feed, so that the base of the hook can enter between layers of material at or adjacent to the sewing station.

One particular type of sewing machine attachment embodying the present invention will now be described by way of example with reference to the accompanying drawings in which:

15 FIG. 1 is a perspective view of a hook of the kind which the attachment manipulates;

FIG. 2 is a section through the tape to be sewn by the attachment, and includes a hook disposed in position ready for sewing to begin,

20 FIG. 3 is a plan view to a somewhat smaller scale of hook tape sewn by the machine and attachment,

FIG. 4 is a plan view of the machine assembly, with the attachment mounted in position,

25 FIG. 5 is a front view, to a larger scale of part of the attachment, the outline of the machine being shown in chain-dotted lines,

FIG. 6 is an end view corresponding to FIG. 5 and as viewed from the left of FIG. 5,

30 FIG. 7 is a plan view of another part of the attachment,

FIG. 8 is a section along the line 8—8 of FIG. 7,

FIG. 9 is a plan view of a hook at the sewing station, to a much enlarged scale, a subsequent position of the hook being shown in broken lines,

35 FIG. 10 is a diagram illustrating the order in which the stitches are formed which secure each hook in position,

FIGS. 11(a) to (e) are a series of related diagrams illustrating the sequence of operations while the stitches of FIG. 10 are being formed,

40 FIG. 12 is a plan view, to an enlarged scale of the lower end of the hook supply chute shown in FIGS. 4 and 5, and

FIG. 13 is a section along the line 12—12 of FIG. 10.

45 In order readily to understand the nature and function of the attachment it is first desirable to understand the nature of the preferred form of hooks for use with the attachment, a typical form of tape to which the hooks are secured, and a typical form of sewing machine assembly with which the attachment is intended to be used.

50 The preferred form of hook is shown in FIG. 1 and is made from a length of wire. One end portion of the wire is bent into generally square configuration as indicated at 1, one side 2 of the square, the first side, having a gap 3 at one end. A portion 4 of the wire leads from the fourth side 5 of the square in a direction away from the square but in alignment with the first side thereof. After a short distance this portion 4 of the wire is curved upwards as shown at 6, out of the plane of the square 1 and extends back over the gap 3 of the first side of the square 1, parallel with that side but spaced above it. This wire is next bent through a 180° curve 7, while remaining in a plane parallel with that containing the square 1, and then curves downwards again at 8, parallel with the upwardly curved portion 5. The dis-

tance between these parallel portions 5 and 8 lying above the plane of the square is equal to the thickness of the wire. The parallel portions themselves define the outline of the bill of the hook.

The next portion of the wire is formed into a second square 9, which is similar to the first-described, for first, square 1 and lies alongside it in the same plane as the first square. The fourth side 10 of the second square 9 abuts the first side 2 of the first square 1, and where the first side of the first square is gapped at 3 the fourth side 10 of the second square 9 has an upwardly directed joggle 11 which extends part way towards the parallel wires outlining the bill of the hook. Finally the last portion 12 of the wire extends straight beyond the fourth side 10 of the second square 9, and curves upwards, lying completely between the parallel wires 6 and 8 defining the outline of the bill, but terminating a short distance from the 180° curve 7. Thus the two squares 1 and 9 form the base of the hook; and most of the bill is constituted by three portions 6, 12 and 8 of the wire lying alongside one another, but a hole 13, which will hereinafter be referred to as the locating hole, is left between the two outer wires adjacent to the free end of the bill. It will be appreciated that the locating hole 13 is in the shape of a rectangle with a semi-circular extension at one end thereof.

The hooks are stitched to a length of tape to form hook tape. A typical form of tape illustrated in FIGS. 2 and 3 is made from two strips of material, one being a strip 14 of stiffening material and the other being a strip of decorative textile material which is considerably wider than the strip of stiffening material. The strip of textile material is folded lengthwise to form four successive panels disposed side by side. The first panel 15 overlies much of the strip of stiffening material 14, extending across it from one edge of the stiffening material. The second panel 16 lies beneath the stiffening material 14. The third panel 18 extends across much of the stiffening material, and across part of the first panel 15, from the other side edge of the stiffening material, while the fourth panel 19, which is narrower than the third panel 17, is folded to lie immediately beneath the third panel. The first and second panels 15 and 16 of the strip of textile material, together with the strip of stiffening material 14 may be considered as a lower layer 19, while the third and fourth panels 17 and 18 of the textile material may be considered as an upper layer 20, the upper layer typically extending across a part of the lower layer and about two-thirds of the width of the lower layer.

In the manufacture of hook tape the bases of the hooks are inserted between the two layers of the tape, and as shown in FIGS. 2 and 3 the bills project from between the layers, extend upwards past the free edge 21 of the upper layer 20 and over that part of the upper layer adjacent to that edge. The hooks may be at uniform intervals along the tape as shown in FIG. 3 or at varying intervals. The hooks are secured in position by stitching which, between successive hooks, comprises a main line of stitches 22 extending through both layers 19 and 20 of the tape, closely adjacent to the free edge 21 of the upper layer 20. The main line of stitches 22 is closer than the bases of the hooks to the free edge 21 of the upper layer 20 of the tape.

Where a hook is present two groups of stitches 23 (each for example comprising five stitches) are formed which extend transversely of the tape and lie on the

side of the main line of stitches 22 further from the free edge 21 of the upper layer 20. These groups of stitches 23 secure to the tape those parts of the bases of the hooks which lie closest to the free edge. The two groups of stitches 23, one on each side of the bill of the hook, are interconnected by a few (for example three) stitches 24 which are parallel with the main line of stitches 22 but are spaced further from the free edge 27 of the upper layer of the tape than the main line of 10 stitches. One of these few stitches 24 secures the tape the two adjacent sides 2 and 10 of the squares 1 and 9 constituting the base of the hook. These few stitches 24 lie just to one side of the free end of the bill of the hook, so that the bill interferes neither with the passage of the sewing needle through the tape nor with the formation of these few stitches.

The stitching may conveniently be effected with the aid of a swing-needle sewing machine. The tape is fed through the machine while the needle forms the main line of stitches 22 without swinging. When a hook is reached the tape feed stops and the needle swing from side to side. The tape feed starts again while a few stitches 24 are formed with the needle swung to one side. The tape feed stops a second time and the needle again swings from side to side. Finally the tape feed resumes with the needle in its original position and the main line of stitches 22 is continued to the next hook.

Conveniently the intermittent tape feed mechanism 30 and the means for controlling the swinging movement of the needle may be similar to those described in our co-pending British Patent Application No. 54,928/71 (corresponding to United States Patent Application Ser. No. 308,848). A swing-needle machine with control means of that kind is illustrated in plan in FIG. 4. The sewing machine itself is of the conventional construction having an upright pillar on the right and an arm 25 extending to the left and carrying at its left hand end a vertically reciprocable needle carrier which can be swung to the left and right.

As the control means is fully described and illustrated in said application it will not be described here in detail. Briefly, however, there is a continuously driven shaft 26 which carries an eccentric device 27 which drives a pawl engaging a ratchet wheel on a lay shaft 28 and causing the lay shaft to rotate intermittently. The lay shaft 28 drives the upper roller 29 of a pair of feed rollers behind the sewing station of the machine. In use the tape passes between the feed rollers and is pulled 45 by them through the sewing station the tape normally moving a short distance each time the needle is withdrawn from the work. The shaft 26 also drives gears in a gear box 30. A continuously rotating shaft extending from the gear box 30 continuously drives a timing chain 31 having spaced lugs (not shown). The lugs intermittently rotate a driven wheel 32 cam shaft 33. On each occasion the cam shaft 33 rotates 180°. A cam 34 on the shaft 33 engages a follower device 35 which can cause the pawl to be lifted from the ratchet wheel and can thus cause the intermittent rotation of the lay shaft 28 to cease temporarily.

A chain wheel 36 at the front end of the cam shaft 33 is linked by a chain 36 to a similar chain wheel 38 at the rear end of a cam shaft 39 which is mounted on the arm 25 of the machine. The front end of the cam shaft 39 carries a cam 40 (see also FIG. 5) which, through the intermediary of an appropriate follower and linkage

(not shown) controls the lateral swinging of the needle. The machine itself is continuously driven from the shaft 26 through the intermediary of an internally toothed belt 41.

When this type of machine and assembly is used in the manufacture of hook tape of the kind described above and illustrated in FIGS. 2 and 3 the tape is fed through the sewing station with the gap between the upper and lower layers 20 and 19 of the tape opening towards the left as viewed in FIG. 4. The bases of the hooks are introduced between these layers from the left and just in front of the sewing station.

The hooks are supplied to a hook-supply station a little to the left of the tape and a little way in front of the sewing station. The hooks pass to the hook-supply station down a chute 41 fed from a hopper (not shown) disposed above the level of the machine and mounted on a bracket 42. The chute comprises a bar 43 of an electrically insulating plastics material (see FIG. 13) formed on its underside with a longitudinally extending groove 44 of inverted T-shaped cross-section. The bills of the hooks lie in the upright part of the groove and the bases lie in the lateral, transverse parts. The hooks are retained in the groove 44 by longitudinally spaced closure plates secured to the underside of the bar, one of the closure plates 45 being shown in FIGS. 5 and 13. Some of the closure plates, or parts of them are of electrically conductive material, and an electrical circuit is formed through those plates or parts and is completed by the wire hooks themselves. If the supply of hooks fails the circuit breaks and the machine is automatically stopped.

The chute 41 is inclined downwards and to the right, and its lower end portion 46 is curved to lie horizontally. At the lower end portion the groove 44 is made to extend right through the bar so that the bills of the hooks become accessible through the groove from above. A slotted spring plate 47 overlies the lower end portion of the bar 43, its slot being aligned with that in the bar. The free end portions of the plate 47, on each side of the slot, are bent downwards to close the ends of the lateral parts of the groove 44. The base of the lowermost hook in the chute abuts the end portions of the spring plate 47 and the hook is then in what is referred to as the hook-supply station. If the hook is forcibly moved to the right, out of the chute 41, the free end of the spring plate 47 rises slightly to allow the base of the hook to pass, but snaps down again to prevent the escape of the next following hook.

The sewing machine attachment which is the main characteristic feature of the present invention is designed to engage the bill of the hook at the hook-supply station, to move it forcibly to the right, thus removing it from the chute and causing its base to be inserted between the layers 20 and 19 of the adjacent tape, to move it in the direction of tape feed until it reaches the sewing station and to hold it in the sewing station while the first few of the laterally extending groups of stitches, which will secure it in place, are formed, and to release that hook and return to the hook-supply station to engage the next hook.

At the sewing station the bed of the machine is formed with a transversely extending hole 48 through which the needle descends when stitches are to be formed.

The attachment comprises a rectangular base plate 50 which, when it is in use, is secured to the bed of the

sewing machine a little to the right of the sewing station. A slide bed 51 is mounted on the base plate 50 and comprises a smaller rectangular plate formed (as best seen in FIG. 8) in its upper surface with a broad shallow groove of rectangular cross-section which extends in a transverse direction, that is in a direction transverse to the direction of tape feed. The rear right hand corner of the grooved plate constituting the slide bed 51 is pivoted to the base plate of the attachment by means of a vertically extending pivot pin 52. A lever 53 having two arms of equal length at right angles to each other is also mounted on the base plate 50 and is disposed in front of the slide bed 51. A vertical pivot pin 54 extends through the lever at the junction of its two arms and into the base plate. The first arm 55 of the two arms of the lever 53 extend forwards from the pivot 54, and the second arm 56 extends to the left of the pivot 54 and has at its free end a rearwardly extending convex projection which engages the adjacent side of the slide bed 51. When the first arm 55 is moved to the left the second arm 56 pushes the slide bed 51 in a clockwise direction as viewed from above. This clockwise movement is limited by an adjustable screw stop 57 mounted on the base plate 50 at the middle of the rear edge thereof, the stop engaging the rear side of the slide bed 51. The screw stop 57 is of tubular shape and contains a helical compression spring which urges the slide bed 51 in a counter-clockwise direction. A second adjustable screw stop 58 is mounted on the base plate 50, at the middle of the front edge thereof, and engages the front of the second arm 56 of the lever 53 immediately opposite the convex projection. Thus the slide bed 51 is normally pressed by the spring against the second arm 56 of the lever 53 which is in turn pressed against the second screw stop 58. The stops 57 and 58 are adjusted so that the maximum pivotal movement of the slide bed 51 is only a very few degrees.

A slide 60 is mounted in the groove in the slide bed 51 and is retained in the groove by two spaced straps 51 extending over the mouth of the groove. An arm 62 projects from the right hand end of the slide 60, and comprises a strip of steel with its main plain vertical and extending transversely of the machine. The right hand end face of the arm 62 is vertical and constitutes a bearing face for engagement by a roller 63 as described below. A helical tension spring (not shown) engages the arm 62 and urges it to the right.

A pair of spaced lugs 64 project upwards from the central part of the slide 60, between the straps 61, and are formed with aligned holes for a pivot pin 65 which extends through them with its axis horizontal and extending in a front to rear direction, that is in a direction parallel or substantially parallel with the direction of tape feed. A relatively long rocking lever 66 is pivoted near its centre to the pivot pin 65 and extends in a transverse direction. A leaf spring or a helical compression spring (not shown) acts between the right hand part of the rocking lever 66 and the slide 69 beneath it so as to urge the right hand part upwards and the left hand part downwards.

The left hand end of the rocking lever 66 is turned rearwards and on its underside carries a tapered locating peg 67 of a shape and size such as to fit the locating hole 13 in a hook of the kind described above and shown in FIG. 1.

As described below in greater detail, movement of the slide bed 51, slide 60 and rocking lever 66 of the

attachment are each controlled by appropriate cams. The arrangement is such that when the slide bed 51 is in its normal position, and the slide 60 is at the left hand end of its range of movement (a range which is only slightly longer than the width of the hook) the locating peg 66 on the rocking arm is aligned with the locating hole 13 of the hook at the hook-supply station so that when the peg is lowered, on rocking movement of the lever 66, it can enter the hole.

If the slide 60 is then allowed to move to the right the hook engaged by the peg 67 is withdrawn from the hook-supply station at the bottom of the chute 41 and is moved to the right until the base of the hook has fully entered between the layers 19 and 20 of the tape a little way in front of the sewing station.

The two-armed lever 53 controlling the slide bed 51 can then be rocked to move the slide bed clockwise as viewed in plan so that the hook is carried rearwards, that is in the direction of tape feed, to the sewing station, where it can be held while the first stitches securing it in place are formed.

FIG. 9 shows in somewhat diagrammatic form the relationship between a hook 48 when the hook is carried by the attachment to the sewing station. The two alternative positions which the needle can take up when stitches are to be formed are indicated at 69 and 70. When the hook is in the position shown in full lines the first group of stitches 23 is formed. Subsequently the hook is carried by the tape to the position shown in broken lines, in which position the second group of stitches 23 is formed.

The right hand end of the rocking lever 66 can be depressed to raise the locating peg 67 from the hook, and the slide bed 51 and slide 60 can be returned to their initial positions described above so that the peg 67 is ready to be lowered into the locating hole 13 of the next hook at the hook-supply station.

This cycle of movements is controlled by cams mounted on the shaft 39. The cam 71 for controlling the movement of the slide bed 51 is immediately in front of the cam 40 for controlling the swinging movement of the needle carrier, while the cam 72 for controlling the movement of the rocking arm 66 is immediately behind the cam 40. The lowermost part of the cam 71 is engaged by an associated cam follower which comprises a roller 73 mounted at the right hand end of an arm 74, the left hand end of which is mounted on a shaft 75 parallel with the cam shaft 39 and mounted in a bracket 76 extending below the arm 25 of the sewing machine. Similarly the lowermost part of the cam 72 is engaged by a roller at the right hand end of an arm 77 which is also mounted on the shaft 75.

The arm 74 is clamped to the shaft 75, and also clamped to that shaft is a vertically depending arm 78 having a horizontal, transverse adjusting screw 79 at its lower end. This screw is so positioned as to engage the right hand side of the arm 55 of the lever 53 which controls the pivotal movement of the slide bed 51. As the cam follower arm 74 moves downwards, therefore, the slide bed 51 moves clockwise as viewed from above.

The arm 77 is loosely pivoted to the shaft 75 and, at a position a little to the right of the shaft, carries a depending arm 80 with a vertical adjusting screw 81 at its lower end. This screw 81 is so positioned as to engage the right hand part of the rocking lever 66 a little to the right of the base plate 50 of the attachment, the position being indicated by the chain-dotted circle in FIG.

7. As the cam follower arm 77 moves downwards, therefore, the locating peg 67 is raised.

The cam 82 for controlling movement of the slide 60 is mounted near the rear end of the cam shaft 39, behind the arm 25 of the sewing machine. The lowermost part of cam 82 is engaged by a cam follower comprising a roller mounted at the right hand end of an arm 83, the left hand end of which is mounted for pivotal movement on a shaft 84, parallel with the cam shaft 39 and mounted on a part of the bracket so as to be disposed somewhat above and to the right of the shaft 72 on which the arms of the other two cam followers are mounted. The shaft 84 extends forward only as far as the middle of the sewing machine arm 25, and carries a depending arm 85 at its forward end. The depending arm 85 carries the roller 63 at its lower end. When the cam follower is pushed downwards the roller 63 moves to the left pushing the slide 60 before it.

The timing of the machine is such that on each occasion a hook is to be sewn to the tape and the cam shaft 39 rotates through 180° the machine sews fifteen stitches. The sewing pattern formed by these stitches is shown diagrammatically in FIG. 10, the numerals in circles being the numbers of the successive stitches from 1 to 15. At the start the needle carrier is in its left hand position, the slide bed 51 is in its normal, forward position, the slide 60 is in its right hand position, and the locating peg 67 is engaging a hook which it holds just in front of the sewing station.

FIG. 11 illustrates the sequence of events during the sewing of the fifteen stitches. The line 11(a) is a developed view of the edge of the cam 71 which controls the forward and backward movement of the locating peg 67. The lines 11(b) and 11(c) are similar developments of the cams 72 and 82 respectively, these controlling the raising and lowering of the locating peg, and the lateral movement of the peg respectively. The row of squares 11(d) serve to indicate the position of the peg 67 at any stage. Each square is divided into four smaller squares, and one of these contains a circle which represents the peg 67. When the circle is in one of the two left hand squares the slide 60 is in its left hand position and when the circle is in one of the two right hand squares the slide is in its right hand position. This movement is of course correlated with the line 11(a). Similarly, when the circle is in one of the two lower squares the slide carrier 51 is in its forward position and when the circle is in one of the two upper squares the slide carrier is in its rearward position. This is correlated with the line 11(c). Each circle is filled in, shaded or open. When a circle is filled in it signifies that the locating peg 67 is in its lowermost position and is in engagement with a hook. When a circle is open it signifies that the peg is in its uppermost position and is disengaged from the hook. Finally, when a circle is shaded it signifies that the peg is at an intermediate height. This correlates with the line 11(b).

Each of the numbers in circles, like the numbers in FIG. 10, represents the number of the stitch being formed at the particular stage in the cycle of stitch formation. It must be understood that each of the box diagrams in the row 11(d) represents the position of the peg 67 at the time when the formation of a stitch finishes and the needle is descending into the work at the beginning of the formation of the next stitch.

Finally the row of diagram 11(e) illustrate the positions of each successive hook in relation to the needle

hole 48 from the time it is first engaged by the peg 67 at the hook-supply station to the time it has been sewn in place and moves away from the sewing station. The position of the next hook is also shown starting from the moment when the peg 67 starts to engage it at the hook-supply station.

In order to emphasise that the cycle of events is repeated, and in order to make it quite clear what happens between the end of one cycle and the beginning of the next cycle, the sequence of stitches shown in FIG. 11 does not have stitch number one at the left hand side of the Figure.

The sequence of events is as follows, each stitch being considered as ending with the downward movement of the needle through the work to begin the formation of the next stitch:

1. The tape is fed rearwards, and at the same time the slide bed 51 moves rearwards (or clockwise) to carry the hook to the sewing station.
2. The tape feed ceases and the needle moves to the right.
3. The needle moves to the left.
4. The needle moves to the right.
5. The needle moves to the left while the locating peg 67 is partially lifted from the hook.
6. The needle moves to the right while the raising of the from the 67 from the hook is completed.
7. The tape feed starts again while the slide bed 51 returns to its normal position and the slide 60 is moved to the left.
8. The tape feed continues.
9. The tape feed still continues.
10. The tape feed ceases and the needle moves from the left while the locating peg 67 starts to be lowered into the locating hole 13 in the next hook at the hook-supply station.
11. The needle moves to the right while the locating peg 67 is lowered fully into the locating hole.
12. The needle moves to the left while the slide 60 also moves to the right, carrying the base of the next hook between the layers of the tape in front of the sewing station.
13. The needle moves to the right.
14. The needle moves to the left.
15. The tape feed starts again.

Normal step-by-step feed of the tape can then continue until the next hook is to be sewn in position, whereupon the cycle is repeated. It will be noted that while the line of stitches 23 is formed, the next hook to be sewn in place is held with its base between the layers 19 and 20 just in front of the needle hole 48.

Two additional devices associated with the attachment must also be described. The right hand end of the rocking lever 66 extends to the right of the vertical adjusting screw 81 which operates the lever. Above the right hand end of the rocking lever 66 is mounted a micro-switch (not shown) which can be operated by excessive upward movement of the right hand end of the rocking lever, but is not operated in normal use of the attachment. If, however, there is no hook at the hook-supply station, then when the locating peg 67 is lowered it can travel further downwards than usual causing the right hand end of the lever to operate the micro-switch. This operation of the switch is arranged to stop the sewing machine.

The other device enables a hook to be omitted at will. This is particularly useful when the sewing pattern for

hook attachment is being checked. A pair of transversely spaced lugs 86 are mounted on the base plate 50 of the attachment just to the rear of the pivot pin 52 and to the right of the first screw stop 57. A horizontal pin 87 extends transversely between the lugs 86 and carries the rear end of a trip lever 88 which extends forwards over the rocking lever 66 a little to the right of its pivot 65 but to the left of the place where it is engaged by the vertical adjusting screw 81 which normally operates the lever. A thumb-plate 89 is mounted on the forward end of the trip lever, and when this is depressed it prevents the locating peg 67 entering the locating hole 13 in a hook and thus prevents hook being withdrawn from the hook-supply station. This, however, does not cause the sewing machine to stop.

If there is a malformed hook at the hook-supply station such that it cannot be correctly engaged by the locating peg 67, then when the slide 60 moves to the right the hook remains at the hook-supply station and the rocking lever 66 tilts to operate the micro-switch referred to above. This causes the machine to stop. When the malformed hook has been removed, the thumb-plate 89 can be depressed to raise the locating peg 67, and a replacement hook can be placed beneath the peg and engaged by the peg when the thumb-plate is released again. The machine can then be re-started and can continue operation with a hook being missed from the row of hooks stitched to the tape.

It will be observed from FIG. 3 that the central switch 30 of the three stitches 24, that is the stitch numbered eight in the pattern of stitches shown in FIG. 10, is rather longer than the other two. Such elongation may not always be necessary though it is present in the form of tape shown in FIG. 3. In order to effect this change 35 in stitch length there is a vertically movable bar (not shown) just in front of the feed rollers. The tape passes over this bar on its way between the sewing station and the feed rollers. The height of the bar is controlled by a cam 90 immediately in front of the cam 35 on the shaft 33. When a short stitch, such as either of stitches numbers seven and nine, is to be made the bar is lowered, and when a long stitch, such as stitch number eight is to be made the bar is raised.

I claim:

1. For use with a sewing machine including a needle a device having utility in the sewing to articles of hooks of the type comprising a base and a bill extending upwards from one side of the base and over part of the base, the base having an attachment portion through which the sewing machine needle can pass, the device comprising hook supply means operative to supply hooks sequentially to a hook supply station, hook engaging means operative to engage the bill of a hook disposed at the hook supply station, to move the hook from that station to a sewing station where the attachment portion is aligned with the sewing machine needle, to release the hook and to return to the hook supply station for a further hook.

2. A device according to claim 1 in which the hook engaging means has a head operative to engage the bill of a hook when it is lowered onto that bill, and in which there is provided operating means operative to cause the head to be raised, and lowered in synchronism with the operation of the sewing machine.

3. A device according to claim 2 including a lever carrying said head and mounted for pivotal movement on a support, and support operating means operative to

move the lever and head laterally between a first position in which the head is aligned with the hook supply station and a second position in which the head is aligned with the sewing station.

4. A device according to claim 3 including a carriage on which said lever is mounted for movement between a forward position in which the head when in its second position is operative to hold a hook in front of the sewing station and a rearward position in which the head when in its second position is operative to hold a hook at the sewing station; and carriage operating means operative to move the carriage between said forward and rearward position.

5. A device according to claim 1 in which the hook supply means comprises a chute having a longitudinally extending passageway substantially of inverted T-shape in cross-section, the narrow portion being operative to receive the bills of the hooks and the broader portion being operative to receive the bases of the hooks.

6. A device according to claim 5 in which the hook supply station is at one end of the chute, there being catch means at the hook supply station operative to prevent the unwanted escape of a hook at the hook supply station but capable of releasing that hook to enable the hook to be removed by the hook engaging means.

7. A device according to claim 1 including an intermittently rotatable drive shaft, a plurality of cams rotatable in unison by said drive shaft, and cam followers for said cams, the movement of the hook engaging means being controlled by the movement of the cam followers.

8. A device according to claim 7 in which there is also a cam and cam follower assembly operative to control the lateral swinging movement of the sewing machine needle, the cam of said assembly being rotatable by said drive shaft in unison with the other cams.
